SAFETYPIN

Robert V. Ford, San Francisco, Calif.

Application April 24, 1935, Serial No. 17,956

8 Claims. (Cl. 24—158)

This invention relates to a safety pin having a clasp head thereon to prevent the pin becoming unintentionally opened.

An object of the invention is to provide an improved type of safety pin which will securely hold and cannot be accidentally detached when in use.

A still further object of the invention is to provide a safety pin that will be superior in point of simplicity, inexpensiveness of construction, positiveness of operation, and facility and convenience in use and general efficiency.

In this specification and the annexed drawing, the invention is illustrated in the form considered to be the best, but it is to be understood that the invention is not limited to such form, because it may be embodied in other forms; and it is also to be understood that in and by the claims following the description, it is desired to cover the invention in whatsoever form it may be embodied.

In the accompanying drawing:

Fig. 1 represents a side elevation of a safety pin constructed in accordance with my invention, and showing the same in the closed position.

Fig. 2 is a side elevation of the pin with the clasp portion removed therefrom.

Fig. 3 is a section taken through Fig. 1 on the line 3—3.

Fig. 4 is a side elevation of a pin in the closed position, and showing the clasp moved to a point where the pin may be either opened or closed.

In detail the construction illustrated in the drawing comprises a safety pin formed of two side members 1 and 2, connected at one end by a spring ring 3, said parts being preferably composed of spring wire in the usual manner. The side member 1 is pointed at one end in the manner of an ordinary pin as shown at 4, and the other side member 2, which constitutes the back of the pin and handle therefor, is provided at one end with a transverse loop or bend 5, a leg disposed at a slight angle to the member 2 and constitutes a spring portion 6, and the terminus 6'. The terminus of the spring portion 6 lies substantially at right angles to the side members 1 and 2 and forms a guard to prevent accidental opening of the side member 1 when the pin is closed, except in the manner to be hereinafter described.

A clasp cowl or casing 8 is adapted to be confined around the side member 2, and the loop 5, as well as the spring portion 6, said clasp 8 being of a flattened longitudinal shape and having opposite sides 9 thereof crimped or bent in under

the spring portion 6, to hold the same on the pin assembly. The forward portion of the clasp 8 is slotted as at 10, and the portion of the clasp 11 immediately below the slot 10, in vertical alignment with the pointed end of the side member 1, to prevent dislodgement of the pin from said socket when the clasp 8 is in the closed position shown in Fig. 1.

The upper side of the side member 2 is either bent or formed with a projection 12 thereon, which lies within a recess or notch 13 on the upper side of the clasp 8. When the projection 12 registers with the notch 13, as shown in Fig. 1, then the pointed portion of the side member 1 may not be opened or closed. In order to open the pin, the clasp 8 is moved axially outward on the side member 2 of the pin, by disengaging the projection 12 from the notch 13, into the position shown in Fig. 4. The spring portion 6 of the side member 2 normally maintains the projection on the side member 2 in registry with the notch 13. Of course this position may be changed by moving the clasp 8 endwise on the pin, after overcoming the tension of the spring portion 6. The distance between the looped portion 5 of the side member 2 and the terminus 6 thereof, regulates the distance which the clasp 8 may slide on the pin when the clasp member moves from the closed position shown in Fig. 1 to the opened position shown in Fig. 4.

In operation the pointed portion of the pin is first opened by sliding the clasp into the position shown in Fig. 4, after which the pointed portion of the pin is passed through a garment or other article, in the usual manner and pressed down into the position shown in Fig. 4, after which the clasp 8 is moved into the closed position shown in Fig. 1. The pin is detached from the garment by reversing the sequence of operation heretofore described.

With my pin, it is impossible for the same to become accidentally opened, inasmuch as the clasp 8 cannot be moved except by a force sufficient to overcome the tension of the slanted spring portion 6 of the side member 2, against the crimped portion 9 of the clasp, and to permit the disengagement of the notch 13 from the projection 12. The terminus 6 of the spring portion also functions as a guard which maintains the pointed end of the side member 1 in its socket and holds the same against accidental dislodgement, as well as a guide for directing the pointed end of the side member 1 into the socket 11.

Having thus described this invention, what I claim and desire to secure by Letters Patent is:

55

1. A safety pin comprised of two side parts having a spring connection at one end, one of said parts being pointed at an end thereof, and the other part being formed into an inwardly directed loop and relatively straight leg in the same plane with the aforesaid side parts; and a clasp slidably confined on the side part having the loop and leg thereon and being adapted to receive the pointed end of the other side part therein, whereby in 5 by in one position of the clasp the pointed end of the pin may be opened and in the other position said pointed end is held closed; a projection on one side part engaging a notch in the clasp for holding said clasp in a position against movement and thereby preventing the pointed end of 10 the side part from being opened.

2. A safety pin comprised of two side parts having a spring connection at one end; one of said parts being pointed at an end thereof, and 20 the other part being formed with a spring guide thereon in the same plane with the side parts; a clasp mounted on said spring guide for holding the side part having the pointed end in the closed position, said clasp being slidable whereby the 25 pointed end of the side part may be disengaged therefrom and brought into the opened position; and a projection on one side part engaging a notch in the clasp for holding said clasp in a position against movement and thereby preventing the pointed end of the side part from being 30 opened.

3. A safety pin comprised of two side parts having a spring connection at one end; one of said parts being pointed at an end thereof, and the 35 other part being formed into an inwardly directed loop and relatively straight leg in the same plane with the aforesaid side parts; a clasp slidably confined on the side part having the loop and leg thereon and being adapted to receive the pointed 40 end of the other side part therein, whereby in one position of the clasp the pointed end of the pin may be opened and in the other position said pointed end is held closed; and coengaging means on one of the side parts and clasp for holding 45 said clasp in a position against movement and thereby preventing the pointed end of the side part from being opened.

4. A safety pin comprised of two side parts having a spring connection at one end; one of 50 said parts being pointed at an end thereof, and the other part being formed with a spring guide thereon in the same plane with the side parts; a clasp mounted on said spring guide for holding the side part having the pointed end in the closed 55 position, said clasp being slidable whereby the pointed end of the side part may be disengaged therefrom and brought into the opened position; and coengaging means on one of the side parts and clasp for holding said clasp in a position 60 against movement and thereby preventing the pointed end of the side part from being opened.

5. A safety pin comprised of two side parts having a spring connection at one end; one of said parts being pointed at an end thereof, and the 65 other part being formed into an inwardly directed

loop and relatively straight leg in the same plane with the aforesaid side parts; a clasp slidably confined on the side part having the loop and leg thereon and being adapted to receive the pointed end of the other side part therein, whereby in 5 one position of the clasp the pointed end of the pin may be opened and in the other position said pointed end is held closed; and a member formed on the end of said loop leg in relation to an end of said clasp whereby when the clasp is in the 10 closed position said member prevents the pointed side part from being opened and when the clasp is in the opened position said member directs the pointed side part into and from the clasp.

6. A safety pin comprised of two side parts having a spring connection at one end; one of said parts being pointed at an end thereof, and the other part being formed with a spring guide thereon in the same plane with the side parts; a clasp mounted on said spring guide for holding 20 the side part having the pointed end in the closed position, said clasp being slidable whereby the pointed end of the side part may be disengaged therefrom and brought into the opened position; and a member formed on the end of said spring 25 guide in relation to an end of said clasp whereby when the clasp is in the closed position said member prevents the pointed side part from being opened and when the clasp is in the opened position said member directs the pointed side part 30 into and from the clasp.

7. A fastener comprising a pair of spring connected side pieces, one of said side pieces having an end recurved to form a spring, a clasp slidably mounted on said recurved portion of the side piece 35 and enclosing and compressing said spring, said clasp having a cowl adapted to receive the end of the other side piece, and said other side piece being of such length that its end will clear at least a portion of said cowl for insertion therein when 40 said clasp is in its extended position and be surrounded by said cowl to prevent its release therefrom when said clasp is in its retracted position, and means cooperating with said spring for preventing accidental sliding of said clasp. 45

8. A fastener comprising a pair of spring connected side pieces, one whereof has its end bent in the plane of said side pieces to form a spring, a clasp slidably mounted on said side piece to enclose and compress said spring so that rotational 50 motion of said clasp on said side piece is prevented, mutually engaging members formed on said clasp and side piece positioned to be urged into engagement by said spring when the clasp is in its retracted position to prevent accidental 55 sliding thereof, and a cowl formed on said clasp to receive the free end of the other side piece, the relative proportions of said second side piece and cowl being such that the free end of said side piece will clear at least one portion of said 60 cowl for insertion therein when said clasp is extended, and will be surrounded by said cowl to prevent its removal when said clasp is retracted.
